CLAIM

The ornamental design for a cup lid with support for smart phone, as shown and described.

DESCRIPTION

FIG. 1 is a perspective view of a cup lid with support for smart phone;

FIG. 2 is a front view thereof;

FIG. 3 is a right side view thereof;

FIG. 4 is a top view thereof;

FIG. 5 is a rear view thereof;

FIG. 6 is a left side view thereof;

FIG. 7 is a bottom view thereof;

FIG. 8 is a perspective view of another embodiment of a cup lid with support for smart phone;

FIG. 9 is a front view thereof;

FIG. 10 is a right side view thereof;

FIG. 11 is a top view thereof;

FIG. 12 is a rear view thereof;

FIG. 13 is a left side view thereof; and,

FIG. 14 is a bottom view thereof.

Broken lines in a long-short-short pattern depict unclaimed boundary lines between claimed subject matter and unclaimed subject matter.

Broken lines in a short-short-short pattern depict unclaimed subject matter.

The cross-hatched pattern extending around the exterior of the bottom rim of the lid represents an embossed texture.

1 Claim, 14 Drawing Sheets
